(57) **CLAIM**

The ornamental design for a bottle with flip top closure, as shown and described.

DESCRIPTION

FIG. 1 is a perspective view of the bottle with flip top closure showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the bottle with flip top closure is included for the purpose of illustrating portions of the article and forms no part of the claimed design.
